HENRY J. KUHLMAN, OF COLESBURG, IOWA, ASSIGNOR TO KUHLMAN & HOLSCHER
MANUFACTURING COMPANY, OF WATERLOO, IOWA.

ADJUSTABLE GANG-FRAME FOR CULTIVATORS.

1,169,840.

Specification of Letters Patent.

Patented Feb. 1, 1916.

Application filed April 7, 1915. Serial No. 19,667.

To all whom it may concern:

Be it known that I, HENRY J. KUHLMAN, a citizen of the United States of America, and a resident of Colesburg, Delaware county, Iowa, have invented certain new and useful Improvements in Adjustable Gang-Frames for Cultivators, of which the following is a specification.

My invention relates to improvements in 10 gang-frames for cultivators, and the object of my improvements is to provide sectional gang-frames so jointed and connected to the main frame, adjustably, as will permit of most effective use in being shifted laterally or moved up or down as a whole or in 15 certain parts, to secure the required actions when desired. This object I have accomplished by the mechanism which is herein-after described and claimed, and which is 20 illustrated in the accompanying drawings, in which:

Figure 1 is a side elevation of a cultivator containing my improved gang-frames, with parts removed or broken away. Fig. 2 is an upper plan view of said machine. Fig. 3 is an enlarged detail side elevation of the jointed connections between the forward and intermediate sections of one of the gang-frames. Fig. 4 is a side elevation 25 of the reverse of the parts shown in said Fig. 3. Fig. 5 is an enlarged top plan view of the parts shown in Figs. 3 and 4. Fig. 6 is an elevation of the said parts taken 30 from the rear obliquely. Fig. 7 is a detail 35 perspective view, enlarged, of the parts of the lever actuated shifting-means of said device.

Similar numerals of reference denote corresponding parts throughout the several 40 views.

The cultivator shown has a tongue 6 mounted in the main-frame bars 7, the latter extending rearwardly and parallel to a location in the rear of the pair of carrying-wheels 48, the latter being rotatably mounted 45 on the spindles of the bowed axle 49, whose bowed part is medially secured to the rear part of the tongue. A cross-bar 5 secured medially to the tongue has its oppositely extended parts secured to the frame-parts 7 and dropped to provide spindles upon which are mounted the rock-bodies 4, which, with the pivot-bolts 3, form universal 50 couplings whereby the forward parts 1-2 of the gang-frame sections are pivotally

connected to said spindles for both lateral and up and down swinging movements.

A cross-bar 50 is mounted across the frame-bars 7 and carries a driver's seat 51, while below the level of the said frame-bars 60 are located a pair of sectional gang-frames, which are placed on opposite sides of the medial longitudinal line of the cultivator. Each gang-frame comprises the sections 1-2, and 11, which have the shovels 13, 65 14 and 15 mounted in echelon therein in proper relation laterally and longitudinally, so that the middle shovel 14 is under the axis of and between the carrying-wheels, with the shovels 13 and 15 located forwardly 70 and rearwardly respectively of said axis. The forward gang-frame section is made up of the rigidly connected rearwardly divergent bars 1 and 2, rigidly spaced and secured at their rear ends by a cross-bar hung 75 between ears 33 and on pivot bolts 34. Under the cross-bar 33 another cross-bar 31 is pivotally connected at its upturned ends to said bars 1 and 2 by means of pintle-bolts 44 to rock up and down and has a disk-shaped part 29 projecting horizontally 80 therefrom, as shown in Fig. 3. The bar 11 of the rear gang-frame section has a similar disk-shaped part 28 on its forward end, which overlies the other disk 29 in registration, and both disks are centrally orificed 85 to receive a pintle-bolt 37, whereby the gang-frame sections are pivotally connected to swing laterally relative to each other.

The rear part of the bar 2 has a socket 63 in which is pivotally mounted the lower end of an arm 24 which is bent over horizontally and rearwardly to overhang the forward part of said bar 11 and orificed to seat the upper end of a headed bolt 25 which is 90 passed downwardly and slidably through a bearing 27 on the bar 11. Said bolt extends downwardly a distance below the bar 11 and has an adjustable stop-nut on its threaded lower end, while a coiled compression-spring 26 is seated about said bolts and engaged between the bar 11 and arm 24. The arm 24 thus forms a pivotal connection between the sections 2 and 11, the spring 26 tending to yieldingly thrust them 100 apart, which thus maintains them in desired positions.

Upon the rear end of the bar 1 is mounted a cylindrical bearing-body 38 in a clamp 110 45 and in whose central hollow is secured a

depending hanger or shank 40, upon whose lower end the forward shovel 13 is detachably mounted. A stirrup 39 is also mounted on the rear end of said bar 1. The numeral 35 denotes an upwardly-curved arm secured by a set-screw 41 on the shank 40 and is at its tip transversely orificed to receive one end of a transverse rod 32 the other end of which is secured in an orifice in another arm 30, which latter is fixedly projected from the disk 28 to be parallel with the arm 35. This rod 32 forms a linking connection between the shank 40 and the bar 11, and capable of some relative movement thereto.

15 The rear section 11 has the middle shovel 14 secured on a shank depending from its middle part, while a like rear shovel 15 is likewise secured on a shank depending from its rear part. The rear end of the bar 11 is forked, with a disk-shaped part 55 of a rearwardly extending bar 12 seated pivotally on a pintle 56 between the forks. The disk 55 has a downwardly-orificed forwardly-projecting finger, with a set-screw 57 passed through its orifice to engage the top of the bar 11, whereby the obliquity of the bar 12 may be adjusted, the disk then being rigidly clamped in said forks by means of the nut upon the pintle-bolt 56. On the rear end 25 of each frame-bar 7 is a depending hanger 8 having its lower end offset and provided with an opening in which the rear end of the arm 12 is movably seated to rock up and down when the gang-frame is moved up and 30 down, and having an adjustable bolt 10 set in one or other of the orifices 9 whereby an adjustment vertically may be made.

I have adopted the following means for shifting the gang-frames laterally, or up 40 and down: A pair of levers 22 are used for this purpose, each lever being mounted to swing either up and down or sidewise. Each lever is pivoted on a pintle 62 to a rack-sector 54, the latter being integral with a 45 cylindrical body 53 having a vertical slot 58 through which the lever is passed forwardly. The forward end of the lever has a row of orifices 21 in either of which one end of a chain 23 is adjustably secured, the lower end 50 of the chain being secured to the rear part of the bar 1. The lever has a finger-piece and movable spring-controlled detent which may be adjustably engaged with any of the teeth on said sector. Referring now to said 55 Fig. 7, the lower solid part of the cylinder 53 is centrally vertically orificed to seat the headed shaft 18, which extends downwardly through a registering central orifice in a cylindrical bearing-body 61 fixed on an 60 end of a cross-bar 61' mounted on the rear part of said tongue 6. The shaft 18 is squared at 59 to interlock with the cylinder 53, but is rotatable in the bearing-body 61, but is provided with a lock-nut 60 to retain 65 it in said seats. The shaft 18 has an offset

crank-part 17 whose depending pin or offset end is seated rotatably and slidably in a bearing 16 on said gang-frame bar 2. The levers 22 may be operated from the driver's seat conjointly with the driver's stirrups 39 70 in the management and control of said gang-frames. Either lever may be rocked vertically to cause its chain-connection 23 to raise or lower the forward gang-frame section 1-2, the pivotally connected gang-frame section 11 and its rearwardly-projecting bar 12 being also raised or lowered, the bar 12 being fulcrumed in the bearing 9. The pivotally-connected sections thus are, 75 when in their lowered positions shown in Fig. 1, suspended with their shovels in the same depth in the ground, but when necessary for the forward shovel 13 to jump a hill of corn or the like, the lever may be employed to swing up the section 1-2, whereby the forward end of the section 11 is rocked up enough to lift the shovel 13 out of the ground without entirely removing the other shovels 14 and 15 from the soil which thus may work along their rows without interruption. When the section 1-2 is elevated, the bearing 16 slides upon the part 17 of the crank-shaft 18 without interference. The spring 26 acts upon the frame-bar 11 to normally keep it level except when swung 80 upwardly by the action of said lever on the bars 1-2 and connections, which maintains all the shovels in their desired positions. The adjustable connection between the bars 11 and 12 also allows such relative adjustment of the rear part of the frame 11 as will cause the rear shovel 15 to properly act and be removed from the ground. Since the lever 22 is, with its supporting-body 53, adapted to be rocked horizontally on the bearing 61, the crank-shaft 18 is rocked thereby to shift the gang-frame sections laterally, and since the crank-connection is with the forward section 1-2, the arc of movement of the forward shovel 13 is greater than those of the other shovels, so that the driver may more easily control same in sidewise movements and with larger scope of play.

Having described my invention, what I claim as new, and desire to secure by Letters 115 Patent, is:

1. In a cultivator, a main frame supported for transportation, a movably connected sectional gang-frame, implements mounted on the sections of said gang-frame 120 in echelon, a connecting-rod between the forward parts of the main frame and gang-frame jointed to each for both vertical and lateral swinging movements, and a rearwardly-directed part on the rear of the 125 gang-frame movably supported on the rear part of said main frame.

2. In a cultivator, a main frame supported on carrying-wheels, a movably connected sectional gang-frame, implements 130

5 mounted on the sections of said gang-frame, the forward part of said gang-frame being jointed to said main frame to permit of both vertical and lateral swinging of that part of the gang-frame, and the rear part of the gang-frame being slidably connected to the main frame for both vertical and lateral rocking movements of the rear part of said gang-frame.

10 3. In a cultivator, a main-frame supported on carrying-wheels, a movably connected sectional gang-frame, implements supported on the sections of said gang-frame, the forward part of the gang-frame being jointed to the forward part of the main-frame for both vertical and lateral swinging, the rear part of the gang-frame having a bar adjustably connected thereto and the latter being slidably connected to 15 the rear part of the main frame for both vertical and lateral rocking, and means for vertically adjusting the connection between said bar and gang-frame.

20 4. In a cultivator, a main frame supported on carrying-wheels, a movably connected sectional gang-frame mounted on said frame for both vertical and lateral movements relative thereto, implements connected to the sections of said gang-frame 25 in echelon relative to the line of movement of the cultivator, and yieldable resilient connecting means between the forward and rear sections of the gang-frame adapted to exert a yielding vertical downward pressure 30 upon the rear section of the gang-frame.

35 5. In a cultivator, a main frame supported on carrying-wheels, a movably connected sectional gang-frame mounted on said frame for both vertical and lateral 40 movements relative thereto, implements supported in sections of said gang-frame, yieldable resilient connecting-means between the forward and rear sections of the gang-frame to exert a vertical yielding pressure on the latter, and a movable connection between 45 the rear section of the gang-frame and the rear part of the main frame adapted to permit lateral and vertical swinging of that part of the gang-frame.

50 6. In a cultivator, a main frame supported on carrying-wheels, a sectional gang-frame mounted under said main frame for both vertical and lateral movements, and connecting-means between the forward and rear ends of the gang-frame and the forward and rear ends of the main frame respectively, adapted to permit the rear part 55 of the forward section of the gang-frame to be shifted vertically relative to and without likewise vertically shifting the forward part of the rear section of said gang-frame.

60 7. In a cultivator, a main frame supported on carrying-wheels, a sectional gang-frame located under said main frame and between said wheels, implements mounted in echelon

65 on the sections of said gang-frame, and connecting-means between the forward and rear ends of the gang-frame and the forward and rear ends of the main frame respectively adapted to permit the parts of the gang-frame to be swung sidewise and to permit of lifting and shifting vertically the forward implement more than the other implements to the rear thereof.

70 8. In a cultivator, a main frame supported on carrying-wheels, a movably connected sectional gang-frame located under said main frame, implements mounted on the section of said gang-frame, the forward section of said gang-frame having its forward 75 end swiveled to the forward part of said main frame for both sidewise and vertical swinging, the rear end of the rear section being adjustably movably connected to the rear end of said main frame for both sidewise and vertical rocking movements, and an implement mounted on the rear part of the forward section and movable vertically without vertically shifting the implements 80 on the gang-frame.

85 9. In a cultivator, a main frame supported on carrying-wheels, a movably connected sectional gang-frame located under said main frame, implements mounted in echelon on said gang-frame sections, the gang-frame 90 having its forward end swiveled to the forward part of said main frame for both sidewise and vertical swinging, the rear part of the gang-frame having a vertically and laterally rocking connection with the rear 95 part of the main frame, and yieldable resilient means seated between the connected parts of the said sections adapted to exert a yielding downward vertical pressure upon the forward part of the rear section.

100 10. In a cultivator, a main frame supported on carrying-wheels, a sectional gang-frame mounted under said main-frame, a connecting body of forked form having its forward end swiveled to the forward part 110 of the main frame for both vertical and sidewise swinging, implements mounted on said gang-frame, an implement mounted on one fork of said connecting body, a swivel connection between the rear ends of the 115 other fork and the forward part of the rear section of said gang-frame, a fixed arm on the latter fork bent to overlie said rear section, and a compression-spring seated yielding between said arm and the gang-frame 120 thereunder, the rear part of said gang-frame having a rearwardly projecting vertically adjustable arm movably connected to and supported in the rear part of said main frame.

125 11. In a cultivator, a main frame supported on carrying-wheels, a movably connected sectional gang-frame mounted thereunder and having its rear end swingingly connected to the forward part of said main frame 130

- for both vertical and sidewise swinging, a hanger depending from one of the forks of said section, an implement mounted on said hanger, a universal joint connection between the rear ends of said forks and the forward end of the rear section of said gang-frame, yieldable resilient means engaged between said arm and said rear section to exert a yielding downward pressure on the latter, an implement on the hanger on the other fork, an arm projected forwardly from the

rear section, an arm projected forwardly from the said hanger, a link connecting said arms, and implements mounted in said gang-frame.

Signed at Colesburg, Iowa, this 24th day of March, 1915.

HENRY J. KUHLMAN.
